TIE PLATE FASTENER

Clarence E. Murphy, Cleveland, Ohio

Application February 24, 1938, Serial No. 192,249

1 Claim. (Cl. 85—30)

This invention relates to tie plate fasteners and more particularly to an improved screw spike of the character used for securing railroad tie plates to wooden ties.

5 An object of the invention is to provide a double thread screw spike to be employed as a means of fastening a steel tie plate to a wooden tie with a minimum of damage to the wood, and which has a tight fit in the wood without splintering or cracking the latter.

10 Another object is to provide a holding double thread screw spike for railroad tie plates which may be removed and reinserted in the same hole in a tie and retain a snug fit therein.

15 Another object is to provide a railroad tie plate double thread screw spike which seals the hole in which it is inserted to prevent the entrance thereto of water and the like so as to prevent corrosion of the screw and rotting of 20 the wood.

25 A further object is to provide a railroad double thread screw spike which may be inserted in a drilled hole and which cuts its own thread in the wood.

30 A still further object is to provide a railroad double thread screw spike which is simple in design and construction and inexpensive to manufacture and one which is self-locking in place. Other objects and advantages will be 35 come apparent from the following detailed description of a suitable embodiment of the invention which is illustrated in the accompanying drawing, in which:

Figure 1 is a fragmentary sectional view showing the railroad screw spike of the present invention secured in a railroad tie and holding a railroad tie plate in position;

Fig. 2 is a top view of a head of the double thread screw spike;

40 Fig. 3 is a fragmentary view showing the modified form of head for the double thread screw spike; and

Fig. 4 is a plan view of the head shown in Fig. 3.

45 Referring to the drawing by numerals of reference, the screw spike has a shank portion, indicated generally by the numeral 1, and a head portion, indicated generally by the numeral 2. The shank 1 extends through a tie plate 3 into a 50 wooden tie of the usual character. A rail 5 rests on the tie plate 3 and is secured by a spike 6. Bosses or similar formations 7 formed on the upper side of the tie plate 3 engage the sides of the base of the rail 5 to prevent lateral movement of the rail.

The head 2 of the double threaded screw spike has a squared end 9 preferably longitudinally tapered which receives a suitable tool or implement (not shown) for turning the double threaded screw spike when inserting it in the 5 wooden tie. A radially extending circular collar 10 is formed on the head 2 substantially at the juncture of the shank 1 with the head. A compression spring 11 is received on a cylindrical portion 12 of the shank 1 which is adjacent the 10 collar 10 and is compressed between the collar and the tie plate 3.

The main portion 14 of the shank 1 is of less diameter than the portion 12 and a tapered portion 15 extends between the reduced diameter portion 14 and the large diameter portion 12. The large diameter portion 12 is of a length at least equal to its diameter, and the tapered portion 15 is substantially equal in length to the 20 large diameter portion 12.

A pair or double set of spiral ribs or threads 17 and 18 are formed on the small diameter shank portion 14 and the tapered portion 15. Preferably the ribs or threads 17 and 18 are V-shaped in cross-section and have relatively sharp 25 crests 19. The rib surfaces 20, directed toward the head of the screw from the crests 19, are set at a greater angle with respect to the axis of the screw than surfaces 21 directed toward the tip end 22 of the screw. This formation of 30 the threads 17 and 18 effects a greater holding power and increases the resistance of the screw to being withdrawn from the tie 4. Additionally, it allows for the screw spike to be turned into 35 the tie in less time than required to turn in previously known types of screw spikes.

The diameter across the crest of the threads 17 and 18 is substantially uniform from one end thereof to the other and preferably substantially equal to the diameter of the shank portion 12. 40 For example, diameter A adjacent the tip end 22 of the screw is substantially equal to the diameter B at the beginning of the tapered portion 15 of the shank 1. Additionally, the crest diameter C across the crest of the threads 17 and 18, substantially at the ends of the latter where the taper 15 of the shank merges into the large diameter portion 12 thereof, is substantially equal 45 to the crest diameters A or B. Thus, the threads 17 and 18 do not materially deform or injure the wood fibers of the tie after the initial thread-cutting or forming action of the portions of the double threads adjacent the tip end of the screw spike when the latter is being inserted into the 50 tie.

In order that the crest diameter of the threads on the taper portion 15 of the shank does not increase over that of the diameter across the reduced diameter portion 14 of the shank, the 5 threads 17 and 18 diminish in height as the diameter of the taper portion 15 increases.

In utilizing the double threaded railroad screw spike described, a hole 24 is first drilled in the tie 4. This hole is of a diameter slightly greater 10 than the diameter of the portion 14 of the shank 1 but of less diameter than the portion 12 of the shank and the crest diameter of the double threads 17 and 18. Accordingly, in screwing the fastener into a tie there is substantially no dis- 15 tortion of the wood fibers by the portion 14 of the shank, and the holding action is effected by the double threads 17 and 18 which cut into the wood fibers forming a pair of spiral threads in the wood. The shank portion 14 is substan- 20 tially cylindrical and round in cross-section so that it merely turns as a shaft during the insertion of the screw, there being a clearance 25 between the walls of the hole 24 and the reduced diameter of the shank portion 14.

25 When the taper portion 14 enters the hole 24 the clearance 25 at the mouth of the hole is gradually diminished until finally the taper portion 15 circumferentially engages the wall of the hole 24 and closes the latter, preventing the pas- 30 sage of water and the like into the hole. In effect the taper portion 15 of the shank is wedged into the hole 24 sealing the same against the atmosphere.

In the event that it is desirable to move the 35 rail 5 or tie plate 3 the double threaded fastening screw spike may be removed merely by applying a suitable tool to the squared end 9 and rotating the same in a counterclockwise direction as viewed in Fig. 2. The screw spike is not 40 injured in inserting it into or removing it from a tie so that it may be used a number of times, thus effecting a considerable economy. The novel construction of the shank portion of the screw effects an improved holding action and imparts 45 increased strength thereto and greater durability in use.

Figs. 3 and 4 illustrate a modified construction of head for the screw spike. According to this modification the upwardly projection portion to 50 be engaged by a wrench or other turning implement is rectangular having opposite parallel sides 27 of greater width than opposite parallel sides 28. This construction enables pressure turning implements to obtain a greater grip on the screw 55 spike and facilitates the inserting of the spike into a railroad tie. Additionally, a hipped or peaked end is formed on the projecting portion and terminates in a point 29.

An advantage of this modified head construction 60 is that a positive grip is afforded for the implement or tool used in screwing the spike into or out of the railroad tie. It sometimes occurs that the socket of the wrench or tool becomes worn so that the corners of the square 65 head shown in Figs. 1 and 2 become mutilated and rounded and the tool cannot obtain adequate grip thereon. With the rectangular head of Figs. 3 and 4 a non-circular cross-section obtains even when the corners thereof become rounded off in 70 use.

Numerous advantages are obtained by the provision of the substantially parallel, helically arranged threads 17 and 18. This double thread 75 feature reduces the time required to insert the screw spike in the tie or to remove it therefrom

to about half that previously required for single thread fasteners having the same effective length of thread in frictional engagement with the wood of the tie. There is thus effected a material saving in labor when utilizing the spike of the present invention in constructing railroads. Additionally, when initially starting the tie plate fastener of the present invention into the wooden tie both of the threads 17 and 18 simultaneously bite into the wood at the opening into the hole 10 24 and on diametrically opposed sides of the spike. This double action minimizes the tearing or splitting of the wood fibres when starting the fastener so that it obtains a quicker grip in the wood and when finally in place is secured in a 15 tie with greater strength.

The double thread construction also reduces the wear on the wood fibres of the tie since the length of the sliding engagement between the metal threads and wood fibres when inserting the 20 spike is reduced in half over that which prevails in single thread screw spikes having the same effective thread length. Accordingly, the individual wood fibres have a more effective grip on the threads with the double thread construction than obtains with the use of but a single thread. Fasteners or spikes employing but a single thread on the shank must be driven by a hammer for a short distance to start them into the hole in the tie until the single thread engages 30 the wood fibres of the tie with sufficient frictional force to cause the spike to feed itself into the hole when rotated. On the other hand the fastener of the present invention does not require that it be driven into the tie before rotating it by the tool. The diametrically opposed threads 17 and 18 have taper portions thereof adjacent the tip end 22 so that the screw spike affords a sufficiently balanced grip in the hole 35 of the tie to effect a self-feeding action when 40 the fastener is rotated to draw the fastener into the tie.

It is to be noted that the threads 17 and 18 are set at such an angle with respect to the axis of the fastener that the latter must be inserted 45 in a tie and removed therefrom by a twisting or screwing action and cannot be driven by a sledge or mallet without injury to the wooden tie fibres by the threads. For example, the angle of the individual threads with respect to the axis of the 50 screw spike is preferably more than 60° such for example as about 70° as shown. This feature is advantageous in that the slope of the threads is such that the fastener does not work itself loose as would occur with threaded spikes of the character driven into the wooden tie solely by an axial force such as that of a sledge.

Other modes of utilizing the principles of the invention may be resorted to, change being made in the particular details shown and described, 60 various modifications and alterations being contemplated, it being understood that the embodiments shown are given for purposes of explanation and illustration.

What I claim is:

A railroad screw of the character described to be driven by a suitable tool and having a head and a shank, said shank comprising a substantially cylindrical body portion of substantially uniform diameter from end to end thereof and 70 a tapering frusto-conical portion at the tip end of the shank providing a relatively blunt end thereon, and a pair of helical threads formed integrally on the shank and disposed in circumferentially spaced parallel relation to one an- 75

other, said threads being of substantially the same length and each making a plurality of turns about the shank, each of the threads being continuous over the cylindrical portion of the shank 5 and over the frusto-conical tapering end portion of the shank, the crest diameter of the threads on the frusto-conical end portion of the shank being less than the crest diameter thereof on the cylindrical portion of the shank, and said threads 10 having oppositely disposed tapered ends on the frusto-conical end of the shank which decrease in height and the crests of which substantially

merge with the surface of said frusto-conical end portion short of the extreme tip end of said shank portion, whereby the crests of the tapered ends of both threads substantially simultaneously engage the wall portions of a railroad tie hole 5 having a smaller diameter than the largest crest diameter of the threads and into which the screw may be initially inserted and started by hand and serve to progressively draw the cylindrical portion of the shank into the hole upon turning of 10 the screw in the hole.
